Primary Examiner — Mitchell I. Siegel(74) *Attorney, Agent, or Firm* — Dunlap Bennett & Ludwig PLLC(57) **CLAIM**

The ornamental design for a putting aid, as shown and described.

DESCRIPTION

FIG. 1 is a top perspective view of a putting aid;
 FIG. 2 is a bottom perspective view of FIG. 1;
 FIG. 3 is a top plan view of FIG. 1;
 FIG. 4 is a right side elevational view of FIG. 1; the undisclosed left side is a mirror image;
 FIG. 5 is a bottom plan view of FIG. 1;
 FIG. 6 is a front elevational view of FIG. 1; and,
 FIG. 7 is a rear elevational view of FIG. 1.
 The broken lines shown in the drawings depict tee openings that form no part of the claimed invention.
